Primary Examiner — Natasha Vujcic*Assistant Examiner* — Gilbert B Ford(74) *Attorney, Agent, or Firm* — Birch, Stewart, Kolasch & Birch, LLP(57) **CLAIM**

The ornamental design for a tube assembly and connector, as shown and described.

DESCRIPTION

FIG. 1 is a front view of a tube showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top perspective view thereof;

FIG. 8 is a bottom perspective view thereof; and,

FIG. 9 is another bottom perspective view thereof.

The dash-dash broken lines depict portions of the tube assembly and connector that form no part of the claimed design. The dash-dot-dash broken lines are break lines that indicate indeterminate length and form no part of the claimed design.

The use of the symbol on the design article forming no part of the claimed design is a trademark under examination of DCSTAR INC.
